SUBMINIATURE TYPE VACUUM TUBE
STRUCTURE

Ross Wood, East Pepperell, Mass., assignor to
Raytheon Manufacturing Company, Newton,
Mass., a corporation of Delaware

Application May 22, 1947, Serial No. 749,756

10 Claims. (Cl. 250—27.5)

1

This invention relates to electron-discharge devices and more particularly to tubes of the so-called subminiature type, such as are used in pocket radios, hearing aid devices and the like.

The space-saving requirements in devices of the above general character call for tubes one external dimension of which must be very small, but the other external dimension of which may be somewhat larger. For this purpose, tubes with so-called flat bulbs are used. Such bulbs are of somewhat flattened elliptical shape in transverse cross-section, and have major and minor transverse axes.

It is desirable, from the standpoint of tube electrical characteristics, to have a large spacing between the cathode and the anode of a tube. One of the results of increasing the spacing between the cathode and anode of an electron-discharge tube, is an increase of tube anode resistance, this in turn resulting in an increase of the tube amplification factor.

It is, therefore, one of the objects of the present invention to increase the cathode-anode inter-electrode distance of a tube and yet to retain the space-saving advantages obtainable with a flat bulb.

Another object is to devise a flat-bulb tube construction which will have a lower control grid-anode capacitance than constructions heretofore used.

A further object is to devise a novel suppressor-grid structure for tubes of the flat-bulb type.

A still further object is to utilize the suppressor-grid structure of a flat-bulb pentode for supporting the filamentary cathode of the tube, thereby eliminating the need for extra filament-supporting members, thus saving the space normally required for such members. In tubes of the above general character, a minimum of space is available inside the bulb.

An additional object is to devise a yoke structure for supporting the getter, in a tube of the flat-bulb type, which structure functions also as an electrical connection between the two halves of the anode and further as a rigid mechanical connection or fastening between the two anode halves.

The foregoing and other objects of the invention will be best understood from the following description of an exemplification thereof, reference being had to the accompanying drawing, wherein:

Fig. 1 is a vertical cross-section, on a greatly enlarged scale, through an electron-discharge device according to this invention, the electrode as-

2

sembly being shown in elevation and certain parts thereof being broken away;

Fig. 2 is a transverse cross-section taken along line x—x of Fig. 1; and

Fig. 3 is a transverse cross-section taken along line y—y of Fig. 1, with the bulb removed.

Referring now to the drawing, the electron-discharge device or tube of this invention is illustrated as a pentode, and includes an evacuated flat bulb 1, of glass or other suitable material, which is of generally elliptical shape in cross-section, therefore having major and minor transverse axes, or major and minor transverse dimensions, the bulb being somewhat flattened from a true elliptical shape, as shown in Fig. 2. The electrode assembly comprises an anode consisting of a pair of similar parallel planar anode elements 2 and 3, a filamentary cathode 4, a control or #1 grid 5, a screen or #2 grid 6, and a suppressor or #3 grid consisting of a pair of similar parallel slotted members 7 and 8, said grids all being mounted in the path of the electrons between cathode 4 and said anode elements 2 and 3. Upper and lower spaced supporting members 9 and 10, viewing Fig. 1, of insulating material, preferably of mica, provide adequate support and proper spacing for the electrodes. A plurality of resilient projections 11 are provided, suitably spaced around the edges of said supporting members, said projections resiliently engaging the interior walls of bulb 1.

Said anode elements 2 and 3, as shown in Fig. 2, are substantially planar, are disposed on opposite sides of cathode 4, and lie in parallel planes. The planar portions of said elements are rectangular in configuration. Elements 2 and 3 are disposed adjacent the opposite narrow ends of bulb 1 and lie in planes which are parallel to the minor transverse axis of said bulb.

40 In prior constructions of the flat-bulb type, the anode halves have lain in planes which are parallel to the major axis of the bulb, so that the cathode-anode interelectrode distance is measured along the minor transverse axis of the bulb.

45 By placing the halves of the anode element according to this invention, that is to say, so that said halves lie in planes parallel to the minor transverse axis of the bulb 1, the cathode-anode interelectrode distance lies along the major trans-

50 verse axis of bulb 1, thus enabling such distance to be increased as compared to prior constructions, or made a maximum, while retaining the space-saving advantages obtainable with a very small flat bulb of the type of bulb 1. By increasing the cathode-anode interelectrode distance,

the plate or anode resistance of the tube is increased, thereby also increasing the tube amplification factor.

The metallic anode elements 2 and 3 are mounted and supported by the supporting members 9 and 10, and have integral planar tab portions which extend or project beyond members 9 and 10, through suitable apertures provided in said members. Between the members 9 and 10, the two vertical side edges of each of the elements 2 and 3 are bent inwardly at substantially right angles to the planar or main body portion of each of said elements for a short distance, in order to make said elements more rigid, since said elements are very small.

The maximum possible area of the rectangular planar portion of each of said elements 2 and 3 must be of necessity somewhat smaller than would be possible if the elements lay in planes parallel to the major transverse axis of the bulb, due to the flatness of said bulb, but this is immaterial because, in tubes of the type to which this invention relates, the small amount of plate current does not cause the problem of plate dissipation to enter.

In order to electrically connect together the two anode halves 2 and 3, a getter yoke 12 is provided at the top of the bulb. This yoke consists of an inverted U-shaped metallic member, in the top horizontally-extending portion of which are two depressions in which the getter compound 13 is placed. The two vertical legs of said yoke are rigidly secured, as by welding, to the corresponding upper tab portions of anode elements 2 and 3. The lower ends of the legs of yoke 12 bear on the upper surface of supporting member 9, and, since said yoke is relatively rigid, due to its configuration, said yoke helps to support and maintain in position said elements 2 and 3. Since said yoke is relatively rigid and has a rather high resistance to twisting, it supports the elements 2 and 3 in position during the assembly process, before the bottom of the bulb 1 is pressed. In addition to providing electrical and mechanical connection between the two anode halves 2 and 3, the yoke 12 supports the getter compound in position, as above described.

Members 7 and 8 act as the suppressor grid, as above described, and each of these members is a substantially planar metallic member having a single slot extending therethrough, each slot having an area comparable to the area of the planar portion of the anode elements 2 and 3. These slots permit electrons to pass from the cathode 4 to the anode halves 2 and 3. The planar portions of members 7 and 8 are of rectangular shape, as are the slots. Member 7 is mounted parallel to, adjacent, but spaced from, anode element 2, while member 8 is mounted parallel to, adjacent, but spaced from, anode element 3; therefore, members 7 and 8 also lie in parallel planes which are parallel to the minor transverse axis of bulb 1. Members 7 and 8 are mounted between cathode 4 and the corresponding anode elements 2 and 3, so that said members are in the path of the electrons between said cathode and anode elements. Members 7 and 8 are mounted and supported by the supporting members 9 and 10, and similarly to anode elements 2 and 3, have integral planar tab portions which extend or project beyond members 9 and 10, through suitable apertures provided in said supporting members. Between said supporting members, the two vertical side edges of each of the grid members 7 and 8 are bent inwardly substantially at right angles to the planar or

main body portion of each of said elements for a short distance, as shown in Fig. 2, in order to increase the rigidity of said members.

An open-ended trough-shaped or channel-shaped metallic member 14 has its base bearing on the upper surface of supporting member 9 and has its right-hand vertical wall rigidly secured, as by welding, to the upwardly-projecting tab portion of member 7. Member 14 acts as a shield, to reduce or minimize the capacitance between the control grid 5 and the anode element 2; this member also helps to support member 7 in position. A similar trough-shaped member 15 has its base bearing on the upper surface of member 9 and has its left-hand vertical wall welded to the upwardly-projecting tab portion of member 8. Member 15 acts as a shield between grid 5 and anode element 3 and also helps to support member 8 in position. These shield members 14 and 15 need be provided only if the tube is to be used for radio-frequency signals, and may be omitted if the tube is to be used for audio-frequency signals, in which case the upper ends of members 7 and 8 may be maintained in position by bending over the upwardly-projecting tabs thereof or by welding a stop member to such tabs above supporting member 9.

The grids 5 and 6 are wound and supported upon grid side rods 16-16 and 17-17, respectively. These four grid side rods are aligned along the minor transverse axis of the bulb, as shown in Fig. 2, and project through perforations or apertures in the upper supporting member 9 and through correspondingly positioned and spaced perforations or apertures in the lower supporting member 10. The grids 5 and 6 are of flattened tubular construction, as shown in Fig. 2, and said grids have a common longitudinal axis, the major transverse axes of said grids lying in a common plane which also includes the minor transverse axis of bulb 1; the common longitudinal axis of these grids is collinear with the axis of filament 4.

Since the major transverse axes of the grids 5 and 6 lie along the minor transverse axis of the bulb, which bulb axis is very short, there is only a very limited space available for the grids of the tube, since the side rods of the two grids must be spaced not less than a certain minimum distance from each other, for insulating purposes. In a pentode, there must necessarily be three grids, and in the above arrangement of tube elements there is no room for a wound suppressor grid, so that in a flat-bulb construction of the present type the slotted members 7 and 8 described above are used for the #3 grid in place of a wound grid.

By arranging the elements as above described, with the major transverse axis of control grid 5 and the plane of anode elements 2 and 3 both lying in the direction of the minor transverse axis of the bulb 1, the interelectrode spacing between the said grid and the said anode elements will be measured along the major transverse axis of the bulb, thus enabling said interelectrode spacing or distance to be increased as compared to prior structures, thereby lowering the grid-plate capacitance in tubes of flat-bulb construction; this is an important advantage of the construction of this invention.

The filamentary cathode 4, which may have an electron-emissive coating thereon, is connected at its upper end to one end of a conducting coil spring 18, which is coiled around a horizontal support bar 19, the opposite end of said spring 18 being welded to the upwardly-projecting tab of

member 7. Support bar 18 extends substantially parallel to the minor transverse axis of bulb 1, and is in turn supported in position by a vertical support rod 20, the upper end of which is welded to the rear end of bar 18 and the lower end of which is welded to the right-hand vertical wall of shield member 14.

A cross plate 21 is welded to the downwardly-projecting tab of slotted grid member 8, and one leg of an L-shaped metallic bracket 22 is welded to said cross plate, the opposite leg of said bracket extending outwardly from plate 21 to the right to the longitudinal center-line of bulb 1. The lower end of filament 4 is welded to the upper end of a central lead-in conductor 23, which is in turn welded, near its upper end, to the outwardly-extending leg of bracket 22. Thus, the upper end of filament 4 is secured to grid member 7 and the lower end to grid member 8. Said filamentary cathode 4 passes through two substantially triangular slots 24 and 25, respectively, formed, one in the upper and one in the lower supporting member, and by the tension exerted thereon by said spring 16, said filamentary cathode is maintained in the apices of said two triangular slots.

It will be seen, from the above, that the filament 4 is supported or anchored by the slotted suppressor grid members 7 and 8, thus eliminating the special space-consuming filament supporting members necessary in the prior constructions. In tubes of this type, which may for example have an overall maximum bulb length on the order of 1 1/4 inches, a maximum major external dimension on the order of 0.365 inch, and a maximum minor external dimension on the order of 0.285 inch, any design which will save space by eliminating extra supporting members is very advantageous.

A lead-in conductor 26 for the anode elements 2 and 3 is welded to the downwardly-projecting tab of anode element 3, a lead-in conductor 27 for grid 6 is welded to one of the side rods 17 of said grid, the rod 17 at the right in Fig. 1 for example, a lead-in conductor 28 for grid 5 is welded to one of the side rods 16 of said grid, the rod 16 at the left in Fig. 1 for example, and a lead-in conductor 29 for the upper end of the filament and for grid member 7 is welded to an enlarged tab 30 in turn welded to the downwardly-projecting tab of member 7, the lead-in conductor 23 being welded to grid member 8 and the lower end of the filament, as stated above. All of these lead-in conductors are sealed through a flat press 31 formed externally of the bulb 1 at the base of the latter. The electrode assembly is thus retained in place within said bulb 1 and the required external electrical connections are provided for the various electrodes. Leads 21 and 28 maintain grids 6 and 5, respectively, in position in the supporting members 8 and 10.

The suppressor grid of a pentode, in order to perform its intended function of reducing secondary-emission effects, is ordinarily connected to the cathode of the tube. In the device of this invention, it will be seen that both grid members 7 and 8 are connected to the cathode 4, as desired, but grid member 7 is connected to the upper end of the cathode, while grid member 8 is connected to the lower end of the cathode. In other words, member 7 is used as the filament return and member 8 is connected to the lower end of the filament. This means that the two members 7 and 8 will be operated at slightly different potentials, the difference of potential between said members being the voltage drop in the filament 4.

However, it has been found that this difference of potential makes no appreciable difference in the tube characteristics, both members 7 and 8 functioning effectively as suppressor grids.

From the above description, it will be seen that conductor 26 is the anode lead, conductor 27 is the screen or #2 grid lead, conductors 23 and 28 constitute leads for the filament circuit, and conductor 29 is the control or #1 grid lead.

Of course, it is to be understood that this invention is not limited to the particular details as described above, as many equivalents will suggest themselves to those skilled in the art. It is accordingly desired that the appended claims be given a broad interpretation commensurate with the scope of this invention within the art.

What is claimed is:

1. An electron-discharge device, comprising an evacuated bulb, upper and lower spaced supporting members of insulating material inside said bulb, a pair of similar eccentrically-located oppositely-disposed metallic electrode members mounted at their upper and lower ends, respectively, in said upper and lower supporting members, said electrode members having integral portions projecting above the upper supporting member and below the lower supporting member through apertures provided therein, a filamentary cathode passing substantially centrally of said bulb through aligned apertures in said supporting members to points beyond the same, means securing and electrically connecting the upper end of said filament to the upwardly-projecting portion of one of said electrode members, means securing and electrically connecting the lower end of said filament to the downwardly-projecting portion of the other of said electrode members, and a pair of anode elements mounted in and between said supporting members, one of said anode elements being positioned on the side opposite from the cathode of each of said electrode members.

2. An electron-discharge device, comprising an evacuated bulb, upper and lower spaced supporting members of insulating material inside said bulb, a pair of similar eccentrically-located oppositely-disposed planar metallic electrode members mounted at their upper and lower ends, respectively, in said upper and lower supporting members and lying in parallel planes, said electrode members having integral portions projecting above the upper supporting member and below the lower supporting member through apertures provided therein, a filamentary cathode passing substantially centrally of said bulb through aligned apertures in said supporting members to points beyond the same, means securing and electrically connecting the upper end of said filament to the upwardly-projecting portion of one of said electrode members, and means securing and electrically connecting the lower end of said filament to the downwardly-projecting portion of the other of said electrode members.

3. An electron-discharge device, comprising an evacuated bulb, upper and lower spaced supporting members of insulating material inside said bulb, a pair of similar eccentrically-located oppositely-disposed metallic grid members mounted at their upper and lower ends, respectively, in said upper and lower supporting members, said grid members having integral portions projecting above the upper supporting member and below the lower supporting member through apertures provided therein, a filamentary cathode

passing substantially centrally of said bulb through aligned apertures in said supporting members to points beyond the same, a pair of similar anode elements mounted in and between said supporting members, one of said anode elements being positioned on the side opposite from the cathode of each of said grid members, each of said grid members having a slot therethrough of a size of the same order as the area of one of said anode elements, means securing and electrically connecting the upper end of said filament to the upwardly-projecting portion of one of said grid members, and means securing and electrically connecting the lower end of said filament to the downwardly-projecting portion of the other of said grid members.

4. An electron-discharge device, comprising an evacuated bulb, upper and lower spaced supporting members of insulating material inside said bulb, a pair of similar eccentrically-located oppositely-disposed planar metallic electrode members mounted at their upper and lower ends, respectively, in said upper and lower supporting members, said electrode members having integral portions projecting above the upper supporting member and below the lower supporting member through apertures provided therein, a filamentary cathode passing substantially centrally of said bulb through aligned apertures in said supporting members to points beyond the same, a pair of similar planar anode elements mounted in and between said supporting members, one of said anode elements being positioned on the side opposite from the cathode of each of said electrode members, said electrode members and said anode elements all lying in parallel planes, means securing and electrically connecting the upper end of said filament to the upwardly-projecting portion of one of said electrode members, and means securing and electrically connecting the lower end of said filament to the downwardly-projecting portion of the other of said electrode members.

5. An electron-discharge device, comprising an evacuated bulb, upper and lower spaced supporting members of insulating material inside said bulb, a pair of similar eccentrically-located oppositely-disposed planar metallic grid members mounted at their upper and lower ends, respectively, in said upper and lower supporting members, said grid members having integral portions projecting above the upper supporting member and below the lower supporting member through apertures provided therein, a filamentary cathode passing substantially through aligned apertures in said supporting members to points beyond the same, a pair of similar planar anode elements mounted in and between said supporting members, one of said anode elements being positioned on the side opposite from the cathode of each of said grid members, each of said grid members having a slot therethrough of a size of the same order as the area of one of said anode elements, said grid members and said anode elements all lying in parallel planes, means securing and electrically connecting the upper end of said filament to the upwardly-projecting portion of one of said grid members, and means securing and electrically connecting the lower end of said filament to the downwardly-projecting portion of the other of said grid members.

6. An electron-discharge device, comprising an evacuated bulb, upper and lower spaced supporting members of insulating material inside said bulb, a pair of similar eccentrically-located oppo-

sitely-disposed planar metallic electrode members mounted at their upper and lower ends, respectively, in said upper and lower supporting members and lying in parallel planes, said electrode members having integral portions projecting above the upper supporting member and below the lower supporting member through apertures provided therein, a filamentary cathode passing substantially centrally of said bulb through aligned apertures in said supporting members to points beyond the same, means securing and electrically connecting the upper end of said filament to the upwardly-projecting portion of one of said electrode members, means securing and electrically connecting the lower end of said filament to the upwardly-projecting portion of the other of said electrode members, and an anode structure having portions positioned on the sides opposite from the cathode of each of said electrode members.

7. An electron-discharge device, comprising an evacuated bulb, upper and lower spacing supporting members of insulating material inside said bulb, a pair of similar eccentrically-located oppositely-disposed planar metallic electrode members mounted at their upper and lower ends, respectively, in said upper and lower supporting members and lying in parallel planes, said electrode members having integral portions projecting above the upper supporting member and below the lower supporting member through apertures provided therein, a filamentary cathode passing substantially centrally of said bulb through aligned apertures in said supporting members to points beyond the same, means securing and electrically connecting the upper end of said filament to the upwardly-projecting portion of one of said electrode members, an angular bracket member securing and electrically connecting the lower end of said filament to the downwardly-projecting portion of the other of said electrode members, and an anode structure having portions positioned on the sides opposite from the cathode of each of said electrode members.

8. An electron-discharge device, comprising an evacuated envelope, a plurality of electrodes supported in said envelope, said electrodes including a filamentary cathode, a pair of grid elements disposed on opposite sides of said filament, a control grid structure disposed between said cathode and said grid elements and an anode structure disposed beyond said grid elements, said grid elements being insulated from one another, one end of said cathode being secured and electrically connected to an adjacent portion of one of said grid elements, the opposite end of said cathode being secured and electrically connected to an adjacent portion of the other of said grid elements.

9. An electron-discharge device, comprising a flat evacuated envelope having major and minor transverse axes, an electron-emissive cathode supported substantially centrally of said envelope, a substantially planar anode element disposed adjacent a narrow end of said envelope, a grid surrounding said cathode and interposed in the path of the electrons between said cathode and anode, said grid having an elongated shape transverse to said axes, the longer axis of said shape lying in a plane parallel to the minor axis of said envelope, the width of said anode being substantially smaller than the length of said longer axis of said grid shape, said anode also

lying in a plane which is parallel to the minor axis of said envelope.

10. An electron-discharge device, comprising an evacuated envelope, upper and lower spaced supporting members of insulating material inside said envelope, a plurality of electrodes supported in said envelope, said electrodes including a filamentary cathode passing substantially centrally of said envelope through aligned apertures in said supporting members to points beyond the same, a pair of grid elements disposed on opposite sides of said filament and mounted at their upper and lower ends, respectively, in said upper and lower supporting members, a control grid structure disposed between said cathode and said grid elements and an anode structure disposed beyond said grid elements, said grid elements being insulated from one another by said supporting members, one end of said cathode being secured and electrically connected to the upwardly-pro-

jecting adjacent portion of one of said grid elements, the opposite end of said cathode being secured and electrically connected to the downwardly-projecting adjacent portion of the other of said grid elements.
